ASSIGNORS TO KELLER PNEUMATIC TOOL COMPANY, OF GRAND HAVEN,
MICHIGAN, A CORPORATION OF MICHIGAN.

PISTON-ROD TOGGLE FOR FLUID-PRESSURE MOTORS.

1,298,327.

Specification of Letters Patent. Patented Nov. 29, 1921.

Application filed April 29, 1920. Serial No. 377,506.

To all whom it may concern:

Be it known that we, WILLIAM H. KELLER, a citizen of the United States, and ALBERT SCHINKEZ, a former subject of the Emperor of Austria, both residing at Grand Haven, in the county of Ottawa and State of Michigan, have invented certain new and useful Improvements in Piston-Rod Toggles for Fluid-Pressure Motors, of which the following is a specification.

This invention relates generally to a novel construction in fluid pressure motors of the type used in portable drills, pneumatic tools and the like, and relates more particularly to the piston rod connections, known as toggles, which coact with the crank shaft.

The primary object of this invention is to provide a simplified toggle construction and thereby materially lower the cost of manufacture and greatly increase the facility with which they may be assembled or replaced in a complete motor.

Another object is to provide a strong and durable construction which will increase the life of the toggle under severe conditions of service.

These objects we attain by a novel structure the parts of which may be stamped out of sheet metal, and which comprise simplified and strengthened means for mounting them on the piston rod and crank shaft wherein a considerable amount of labor is saved in the manufacturing, assembly and subsequent repair of a motor, and the life of the structure in service is increased.

It is the common practice, in the motors of this class, to arrange a plurality of cylinders about a common crank shaft, the cylinders being angularly disposed in pairs in which the pistons are operatively connected in pairs with one crank bearing. Hinged toggles are usually employed, one overlying the other, which are secured to their respective piston rods by means of a binding nut engaging the toggle ends. In the usual construction it is found that the toggle hinges frequently shear off, and that the binding nuts split under the strain of service. Also, the toggles now commonly used are made of forgings requiring many machining operations in their manufacture, and they are very difficult to assemble in the motor due to their design and the necessarily restricted space in the crank case.

These objectionable features are avoided in the structure disclosed in this invention, as will be apparent, with other advantages, in the following specification, of one embodiment of the invention.

In the drawings, Figure 1 represents in sectional view a pair of pistons, showing the piston rods and toggle connections in elevation. The cylinders, valve mechanism and crank case are indicated in outline as embodied in the preferred structure described in our pending application, Serial No. 228,570, filed April 15, 1918. Fig. 2 represents a side elevation of a piston rod with toggles assembled. Fig. 3 represents in perspective the parts of a pair of toggles. Fig. 4 shows an alternative construction for the outer toggle members.

In Fig. 1, numerals 1 and 2 indicate a pair of cylinders arranged with their axes at an angle and in a common plane. The pistons 3 and 4 operating therein carry piston rods 5 and 6 to which are secured the toggles 7 and 8. Toggle 7 has its bearing directly upon the crank journal 9, while toggle 8 overlies and has its bearing upon toggle 7. A valve mechanism associated with the cylinders is indicated at 10. The crank case, indicated at 11, has two lateral openings 12, which are closed by removable plates and designed to provide access for the assembly or repair of the toggle connections.

The toggles are of two piece construction. The inner toggle 7 comprises two members 13 and 14, each forming half of the bearing 15 and 16 and having lateral extensions 17 and 18. The extensions are perforated at 19 and 20 to receive a clamping bolt. The member 13 has a tongue 21 formed on its outer edge adapted to engage a recess 22 formed in the abutting edge of the member 14, designed to secure them in relative position when assembled. Oiling holes are provided at 23 and 24. Journals are formed at 25 and 26 for the bearings of the overlying toggle 8.

In assembled position the extensions 17 and 18 abut on their inner faces and are adapted to be rigidly clamped to the piston rod 5 by engagement within and abutting the base of the yoke formed by the recess 27 cut in the outer end of the piston rod. The yoke arms are bored transversely at 28, in

register with the holes 19 and 20 in the toggle members. The assembly is secured in position by the clamping bolt 29, having threaded engagement with the yoke. A lock

5 washer 30 may be seated in a recess 31 formed on the yoke, and provided with straps 32 which may be bent up against the lateral faces of the bolt head. A slot 33 may be cut longitudinally at the base of the recess 27, to give uniform bearing of the yoke arms in clamping the toggle members.

The outer toggle 8 also comprises two members 34 and 35, having lateral extensions 36 and 37, perforated at 38 and 39. The two members 34 and 35 are secured to their respective piston rod 6 by means similar to that just described for the members in the inner toggle 7. The members 34 and 35 are formed with curved straps 40 and 41 whose internal surfaces are adapted to bear upon the journals 25 and 26 formed on the inner toggle members. In assembled position the extensions 17 and 18 on the inner toggle members extend through the aperture formed between the straps 40 or 41, as may be selected, and operatively swung therein. The straps 40 are integrally connected at their outer ends by a cross bar 42 which is formed into a wide hook having an inwardly projecting lip 43. The straps 41 also are integrally connected at their outer ends by a curved cross bar 44, adapted to conform to the inner surface of the bar 42 and to interlock the projecting end 45 with the lip 43, thus positively securing the engagement of the members 34 and 35 in their assembled position about the underlying toggle members.

40 In the modified structure shown in Fig. 4, the inner cross bar may be shaped in a roll 44^a, to be embraced within the hook 42^a formed to snugly engage the roll and interlock the toggle members.

It will be seen that we have produced a simplified toggle structure which will be apparent to one skilled in the art as being capable of manufacture by simple and inexpensive die and press operations on sheet metal. It will be evident also that the method of connecting the toggle members to the piston rod greatly simplifies their assembling and repair in a motor, in that the few necessary operations may be quickly and conveniently done through the openings provided in the crank case. This connection likewise provides great rigidity and durability. A further apparent advantage lies in the outerly connected straps forming the outer toggle bearings, with the integral interlocking device extending the full width of the toggle members, thereby providing a strong durable engagement at a point of considerable strain.

We would have it understood that the invention is not limited to the construction

herein shown, as various modifications may be made within the scope of the appended claims.

We claim as our invention:

1. In a device of the class described having two cylinders arranged at an angle to each other, pistons therein, and a crank shaft, the combination of two piston rods, each having an end engaged with one of said pistons, the opposite end forming a yoke, a two-piece toggle connection having a rotatable bearing on said crank shaft and rigidly clamped in the yoke on one of the said piston rods, a two-piece toggle connection having reciprocal bearing on the first mentioned toggle connection and rigidly clamped in the yoke on the other of the said piston rods, and interlocking means carried on the outer ends over the full width of the two members of the second mentioned toggle connection. 70 75 80 85

2. In a device of the class described having two cylinders arranged at an angle to each other, pistons therein, and a crank shaft, the combination of a piston rod in 90 each of said cylinders having engagement with the piston therein at one end, the other end of the piston rod forming a yoke, a transverse bore through the arms of said yoke, a bolt through said bore having screw 95 threaded engagement therewith, a lock washer on said bolt laterally fixed in a recess on the adjacent face of said yoke, a two-piece toggle having a direct bearing on said crank shaft and having lateral extensions 100 thereto, said extensions being in abutting position within the yoke on one of said piston rods and perforated transversely to register with the bore in said yoke and thereby rigidly clamped within said yoke 105 by means of said bolt, a two-piece toggle having its bearing upon the first mentioned toggle and having lateral extensions thereto, said extensions being in abutting position within the yoke on the other of said piston rods and perforated transversely to register with the bore in said yoke and thereby rigidly clamped within said yoke by means of said bolt, and means for interlocking the outer ends of the two members of the second 110 mentioned toggle comprising an integral outer hook on the one member and an integral inner hook on the other member adapted to positively interlock, said hooks 115 extending the full width of the toggle members.

3. A fluid pressure motor having two cylinders in angular relation to each other, pistons therein, a crank shaft, and a crank case, in combination with two piston rods 125 each having an end connected with one of said pistons, the opposite end carrying bolt-secured clamping means, a separable part toggle connection bearing upon said crank shaft and rigidly clamped to one of said 130

piston rods, a separable part toggle connection bearing upon the first mentioned toggle connection and rigidly clamped to the other of said piston rods, interengaging 5 means for locking in operative position the outer ends of the separable parts of the second mentioned toggle connection, said means interengaging over the full width of said parts, and means of access laterally 10 through said crank case adapted to expose said toggle connections for convenient assembly and repair.

4. A portable motor having, in combination, two angularly disposed cylinders, pistons therein, a crank shaft, a crank case having lateral openings therethrough and removable means of closing said openings, two piston rods each being connected to one of said pistons at one end and forming a 20 yoke at the other end, an inner toggle bearing upon the said crank shaft and comprising two members, one member carrying a projecting tongue on its outer end adapted to engage a recess formed in the abutting 25 end of the other member, said members having abutting lateral extensions which are rigidly clamped within the yoke on one of said piston rods, an outer toggle composed of two members each of said members comprising spaced curved straps integrally joined at their base to form lateral extensions, said extensions abutting and being rigidly clamped in the yoke on the other of the said piston rods, said curved straps 30 being adapted to bear upon journals formed on the inner toggle and providing a spaced aperture for the operative connection between the inner toggle and its piston rod, a cross bar integrally connecting the outer 35 ends of the straps of one of said members, forming a hook of the width of said member and carrying an inwardly extended lip at its end, and a cross bar integrally connecting the outer ends of the straps of the other 40 members also of full width and formed to engage the inner face of said hook and interlock therewith by abutting the said lip.

5. Means for connecting a crank with a 50 pair of reciprocating elements comprising an inner toggle and an outer toggle stamped from sheet metal, the inner toggle composed of two complementary members each having a semi-cylindrical bearing portion 55 adapted to embrace the crank, and each having a laterally projecting ear adapted for bolted attachment to a connecting rod, one member having on the side opposite the ear a tongue adapted to engage a corresponding recess in the complementary side 60 of the other member, the outer toggle composed of two complementary members each having spaced curved portions adapted to embrace the bearing portion of the inner 65 toggle, the curved portions integrally joined at their ends to form on one side of each member a laterally projecting ear adapted for bolted attachment to a connecting rod, the opposite side of the curved portions in one member being integrally joined to form 70 a hook of the full width of said member having an inwardly extended locking element, the other member having its complementary curved portions joined integrally to form a cross bar adapted to engage the 75 inner surface and interlock with the said hook over its full width.

6. In a fluid pressure motor, an inner toggle connection comprising two complementary members stamped from sheet metal, 80 each of said members having semicylindrical bearing portions adapted to embrace a crank shaft, the members being formed with lateral ears transversely perforated and adapted to be attached to a piston rod, one 85 of said members having a tongue on the side of the bearing portion opposite the said ear, the second member carrying a complementary recess in its bearing portion to engage said tongue.

7. In a fluid pressure motor, an outer toggle connection comprising two complementary members stamped from sheet metal, each of said members having two spaced straps cylindrically curved and adapted to 90 embrace in bearing engagement an inner toggle, the straps being integrally joined at their ends by cross elements, the two complementary cross elements on one side forming lateral ears transversely perforated 95 and adapted to be attached to a piston rod, the complementary cross elements on the opposite side having interlocking means composed of a curved portion formed on one element having an angularly disposed lip 100 at its end extending inwardly the full width of the member, and a second curved portion formed on the other of said elements adapted to conform to and engage the inner surface of the first curved portion, its end abutting and interlocking with the said lip.

8. In a fluid pressure motor, connecting means between a piston rod and its toggle comprising a piston rod having a bifurcated end forming a yoke adapted to embrace the 115 extended ears of a toggle, a transverse bore through the arms of the yoke registering with holes in said toggle ears, and a recess formed on the outer face of one arm concentrically with said bore, a bolt adapted to 120 pass through the bore and engage the arms of said yoke in rigid clamping engagement with said toggle ears, and a lock washer seated in said recess having lateral projections to be forced against the head of said bolt and prevent rotation thereof.

9. In a fluid pressure motor, a toggle connection comprised of two complementary members each having means of attachment to a piston rod and having spaced curved 130

4
straps adapted to form half of a rotatable bearing, the straps in one of said members being integrally joined to form an outwardly curved hook of the full width of said member and carrying an inwardly extended lip at its end, and the straps in the other of said members being integrally joined to form a complementary hook of similar width adapted to engage the inner face of the first mentioned hook and interlock therewith by abutting the said lip.

10 10. In a fluid pressure motor, a toggle connection comprising two complementary

members having means of attachment to a piston rod and having spaced curved straps 15 forming half of a rotatable bearing, the straps in one of said members being integrally joined by a cross element, and the straps in the other of said members being integrally joined to form a curved hook adapted 20 to receive the said cross element and interlock therewith.

In testimony whereof we have hereunto set our hands.

WILLIAM H. KELLER.
ALBERT SCHINKEZ.
